UNITED STATES PATENT OFFICE.

SABASTIAN COMSTOCK AND EDWIN M. COMSTOCK, OF CASCADE VALLEY,
NEW YORK.

OILER FOR CARRIAGE-AXLES.

SPECIFICATION forming part of Letters Patent No. 284,386, dated September 4, 1883.

Application filed July 16, 1883. (Model.)

To all whom it may concern:

Be it known that we, SEBASTIAN COMSTOCK and EDWIN M. COMSTOCK, of Cascade Valley, in the county of Broome and State of New York, have invented a new and Improved Automatic Oiler, of which the following is a full, clear, and exact description.

The object of our invention is to provide a new and improved device for automatically providing axles, bearings, &c., with a steady and sufficient supply of oil or other lubricant without any waste whatever of the lubricant.

The invention consists in an oil chamber or box secured on the axle, &c., and provided with a tubular valve-plug, adapted to be operated by levers, pawls, a ratchet-wheel, and a cam-ring from the axle, whereby a small quantity of oil will be admitted to the cavity of the axle-box every time the wheel has made a certain number of revolutions.

Reference is to be had to the accompanying drawings, forming a part of this specification, in which similar letters of reference indicate corresponding parts in all the figures.

Figure 1 is a longitudinal elevation of our improved oiler, showing it applied to a wagon-axle. Fig. 2 is a longitudinal sectional elevation of the same on the line *xx*, Fig. 1. Fig. 3 is a cross-sectional view of the same on the line *yy*, Fig. 1.

A box, A, provided at one end with a removable cover, B, is held on the axle C, near the end. The box contains a close-fitting piston, D, secured to a piston-rod, E, having a handle-piece, E', at its outer end, the said piston-rod being surrounded by a spiral spring, F, between the cover and the piston. At the end opposite the one provided with a cover the box A is provided with a transverse chamber, G, containing a tubular plug, H, provided with two apertures, *a*, *b*, at opposite ends in different sides. A channel, *d*, leads from the chamber in the box A to the transverse chamber G at that point at which the aperture *a* is arranged in the tubular plug H. At that point of the chamber G where the aperture *b* in the plug H is placed a fine tube, J, extends to and through the collar K on the axle at the inner end of the hub.

A sliding rod, L, held in a guide, M, on the axle C, has its inner end connected with a lever,

N, pivoted on a pivot, H', formed on the outer end of the plug H, and the said lever extends above the pivot H'. To the ends of the lever N two spring-pawls, O, are fastened, one extending upward and the other downward, and both engaging with the teeth of a ratchet-wheel, P, made integral with the plug. The outer end of the rod L rests against a cam-ring, R, on the inner end of the hub S, and a spring, Q, secured to the guide M and to the rod L, presses the outer end of the rod against the cam-ring. The plug H can be provided with screws for adjusting the apertures *a*, *b* to the desired size.

The box A is provided with a filling funnel-tube, T, closed by a plug, T'.

The operation is as follows: The piston D is withdrawn toward the closed end of the box A, which is then filled with oil. If the piston-rod is released, the spring F, which expands, acts on the piston and forces the same toward the hub, and thus forces the oil into and through the channel *d*. Every time the wheel makes a revolution the cam-ring R on the hub acts on the rod L and forces the same in the direction of the arrow *a'*, and thereby the lever N will be rocked and the wheel P will be revolved one tooth. Thus the wheel P and the plug H will make a revolution for a certain number of revolutions of the wheel. During every revolution of the plug H the aperture *a* of the same will coincide with the end of the channel *d*, and during that time oil can be forced through the aperture *a* into the plug H. Then the aperture *b* will coincide for a short time with the end of the tube J, thus permitting the oil to flow from the plug H through the tube L to the hub. The hub is thus provided with a certain quantity of oil every time the wheel has made a certain number of revolutions. By arranging more or less teeth on the wheel P the device can be adjusted to deliver more or less oil, as thereby the plug H can be adjusted to make a revolution for greater or less number of revolutions of the wheel.

We do not abandon or dedicate to the public any patentable features set forth herein and not hereinafter claimed, but reserve the right to claim the same either in a reissue of any patent that may be granted upon this appli-

cation or in other applications for Letters Patent that we may make.

Having thus described our invention, we claim as new and desire to secure by Letters 5 Patent—

1. An oiler consisting of a box adapted to contain oil, and provided with a valve-plug connected with a rod adapted to be acted upon by a cam on the inner end of the hub, which 10 oil-box is connected by a tube with the axle-box cavity, substantially as herein shown and described.

2. In an oiler, the combination, with a box or vessel adapted to contain oil, of a piston in 15 the said box, a spring for pressing the piston toward that end of the box provided with the outlet-opening, a valve-plug in the box, a rod connected with the valve-plug and adapted to be acted upon by a cam on the hub, and a tube 20 leading from the outlet end of the oil-box to the cavity of the axle-box, substantially as herein shown and described.

3. In an oiler, the combination, with the oil-box A, of the tubular plug H, provided 25 with apertures a b, the lever N, the pawls O,

the ratchet-wheel P, the rod L, the cam-ring R on the hub, and the tube J, extending from the oil-box to the cavity of the axle-box, substantially as herein shown and described.

4. In an oiler, the combination, with the 30 oil-box A, provided with a channel, d, and chamber G, of the tubular valve-plug H, having apertures a b, the lever N, the pawls O, the rod L, the cam-ring R on the hub, and the tube J, extending from the oil-box to the cavity of the axle-box, substantially as herein 35 shown and described.

5. In an oiler, the combination, with the oil-box A, of the piston D, the piston-rod E, the handle E', and the spring F, of the plug H, 40 the ratchet-wheel P, the pawls O, the lever N, the rod L, the opening Q, and the cam-ring R on the hub, substantially as herein shown and described.
